BUFFING AND POLISHING COMPOSITION
AND METHOD OF USING THE SAME

Paul R. Pine, Elyria, Ohio, assignor to The
Chandler Chemical Company, Cleveland, Ohio,
a corporation of Ohio

No Drawing. Application February 7, 1935,
Serial No. 5,493

20 Claims. (Cl. 51—280)

This invention relates to a buffing and polishing composition. In buffing, polishing and such treating of brass, copper, nickel, or other base metals, usually for finishing or preparatory to plating, the present practice is to apply on the polishing surface compositions comprising wax, tallow, stearic acid and other well known binders having uniformly distributed therethrough such abrasives as comminuted or finely powdered lime, silica, tripoli and emery dust, and the like, all of which are insoluble in water and alkaline cleaners. Such mixtures applied to the wheel are necessarily transferred by it to the article during the polishing or buffing operation.

After the polishing and buffing operations, the article is washed in a suitable bath, usually an aqueous solution of alkali, which removes the major portion of the composition, the binder, under the action of the alkali bath, being dissolved, emulsified or saponified by the alkali solution so as to free the abrasive. The larger portion of the abrasive is then free to be removed readily and usually is readily washed off mechanically by the same alkali bath. For some reason, however, a very fine film of the insoluble abrasive, especially of the most finely comminuted particles, remains on the article and, if plating is to follow, deleteriously affects the subsequent plating operation. The complete removal of this residual film is very difficult and expensive, requires thorough scrubbing, and is a wholly mechanical operation.

More recently, there has been developed a process known as "bright" nickel plating, in which a bright nickel plate requiring very little or no buffing itself is deposited over a highly buffed surface of the metal product to be bright plated. If the residual film of abrasive above described remains on the surface which is plated by a "bright" process, it tends either to show through the plating coat, or, at least, to cause the plated surface overlying it to have a different appearance from the remainder of the surface, and thus be objectionable to the trade.

Another disadvantage of some prior compositions for polishing and buffing is that they deteriorate when exposed to air for a day or so. For example, many include lime as an abrasive and the lime, when exposed to air, hydrates and carbonates, disintegrating the material or stick in which it is formed for use and rendering it unfit.

One of the most important objects of the present invention, therefore, is to provide a polishing and buffing composition in which not only the binder is soluble, saponifiable, or emulsifiable in

the particular cleaning bath used but also in which all or the larger portion of the abrasive or polishing agent is soluble, preferably in the same cleaning bath, so that the composition in its entirety may be dissolved and thus removed from the product without the necessity of any mechanical action for its removal.

Another object is to provide a material of this character which can be left exposed indefinitely to the air and which, when so exposed, will not deteriorate or disintegrate.

A more specific object is to provide a material having the above characteristics which may be readily molded into the usual stick form and which is sufficiently hard to be applied to the buffing or polishing wheel in the usual manner and without undue waste.

In order to illustrate the use of the invention, it will be specifically described as a composition for use on articles that are to be cleaned by subjecting them to an alkali cleaning bath, the broader controlling characteristics of the elements being defined so that the modifications necessary to be made for utilizing the invention in connection with other industrial cleaning baths are clearly apparent.

As stated above, it is a general practice to subject articles which have been buffed or polished to an alkali cleaning bath comprising the usual industrial aqueous alkali solution of from 3 to 8% concentration. In such a solution, there is a great excess of water available for dissolving a water soluble abrasive material.

As general examples of the present composition as used in connection with an alkali cleaning bath, the binder may comprise stearic acid, tallow, hydrogenated fats and fatty acids, such as hydrogenated cottonseed oil and fatty acids derived therefrom, synthetic fatty acids derived from hydrocarbon, glue and mixtures of the above, and any of the well known binders commonly used for such purposes, and preferably those which remain hard at normal room temperature. The important characteristic of the binder used is that it should be soluble, saponifiable or emulsifiable and preferably in the particular cleaning solution used for the product in the usual concentration suitable for industrial use for such cleaning and that it should be essentially inert or inactive relative to the abrasive used in connection therewith, both while in the stick and while the binder and abrasive are together in the same bath. The above binders are soluble, emulsifiable, or saponifiable in an alkali cleaning bath.

5. A composition for the purposes described, comprising a mass of binder material and comminuted abrasive material distributed therethrough, a substantial part of said abrasive material being soluble in water. 5
6. A composition for the purposes described, comprising a mass of binder material capable of adhering to a rotary polishing wheel when rubbed relatively thereagainst and abrasive material distributed therethrough, said materials being substantially inert with respect to each other when so mixed, and a substantial part of the abrasive material being soluble in the same solution as the binder material. 10
- 15 7. A composition for the purposes described, comprising a mass of binder material soluble, saponifiable, or emulsifiable in an aqueous alkali solution, and comminuted abrasive material soluble in water.
- 20 8. A composition for the purposes described, comprising a mass of binder material capable of adhering to a rotary polishing wheel when rubbed relatively thereagainst and abrasive material distributed therethrough, both of said materials being soluble in an aqueous alkali solution while in the presence of each other therein. 25
- 25 9. A composition for the purposes described, comprising a binder of fatty acid material and comminuted abrasive material soluble in a bath which is both capable of dissolving the fatty acid material and suitable for cleaning an article polished with the composition without deleteriously affecting the surface finish of the article during the period of exposure to the bath required for 30 cleaning the article.
- 35 10. A material for the purposes described, comprising, a binder of fatty acid material and comminuted water soluble salt distributed therethrough.
- 40 11. A material for the purposes described, comprising, by weight, a mixture of stearic acid 10% to 50% and sodium sulphate 90% to 10%. 35
- 45 12. A material for the purposes described, comprising a mixture of stearic acid and sodium sulphate in the ratio, by weight, of about 1 part of stearic acid to about 3 parts sodium sulphate. 40
- 50 13. A material for the purposes described, comprising a binder of fatty acid material, emulsifiable, saponifiable or soluble in an aqueous alkali solution and comminuted abrasive water soluble filler material distributed therethrough, said materials being substantially inactive with respect to each other in the presence of the aqueous alkali solution. 45
- 55 14. A composition for the purposes described, comprising a binder material emulsifiable, saponifiable or soluble in a cleaning agent suitable for cleaning an article polished with said composition without deleteriously affecting the surface 50
- 60 finish of the article during the period of application of the agent required for cleaning the article and comminuted abrasive material distributed therethrough and soluble in the same cleaning agent, said materials being substantially inactive with respect to each other in the presence of the cleaning agent. 55
- 65 15. A composition for the purposes described, comprising a mass of binder material and abra- sive material distributed therethrough, said materials being substantially inert with respect to each other when so mixed, and each of said materials being soluble in liquid cleaning baths suitable for cleaning an article polished with said composition without deleteriously affecting the surface finish of the article during the period of exposure of said article to said baths required for cleaning the article. 60
16. A composition for the purposes described, comprising a mass of binder material and abrasive materials distributed therethrough, all of said materials being substantially inert with respect to each other when so mixed, at least half of the abrasive material being soluble in a 15 cleaning bath suitable for cleaning the article polished with said composition without deleteriously affecting the surface finish of the article during the period of exposure of the article to said bath for cleaning purposes and while in the 20 presence of the other materials in said bath while in the presence of the other materials therein. 25
17. The method of polishing articles against polishing surfaces which includes applying on the polishing surface a quantity of binding material soluble in an alkaline cleaning bath, and water soluble abrasive filler material, polishing the article with said polishing surface, and subjecting the article to an aqueous alkali cleaning 30 bath for a sufficient interval to dissolve and thus remove both materials, whereby the polished surface is clean and unmarred. 35
18. The method of polishing articles against polishing surfaces which includes applying on the polishing surface a polishing composition including abrasive material soluble in a cleaning agent suitable for cleaning the article to be polished without deleteriously affecting the surface finish of the article during the usual time of exposure of the article to the agent for cleaning, polishing the article with said polishing surface, and subjecting the article to said cleaning agent for a sufficient interval to remove the abrasive material, whereby the polished surface is clean 40 and unmarred. 45
19. The method of polishing articles comprising applying to the articles a polishing compound including a mass of binder material and abrasive material distributed therethrough, both of the 50 materials being soluble in a cleaning agent suitable for cleaning the article to be polished, polishing the article with said composition and subjecting the article to the said cleaning agent for a sufficient interval to remove and loosen the 55 composition, whereby the polished surface is clean and unmarred.
20. The method of polishing articles comprising applying to the article a polishing composition including binder material and abrasive filler 60 distributed therethrough, said abrasive and binder being soluble in cleaning agents suitable for cleaning the article to be polished, and being substantially inert with respect to each other in the presence of said cleaning agents, polishing the article with said composition and subjecting the article to said cleaning agents. 65
